DESIGN FOR A TELEPHONE DIRECTORY CABINET

Harry I. Beardsley, Chatham, N. J., and John M. Hayward, Crestwood, N. Y., assignors to Bell Telephone Laboratories Incorporated, New York, N. Y., a corporation of New York

Application November 7, 1936, Serial No. 65,770

Term of patent 14 years

To all whom it may concern:

Be it known that we, Harry I. Beardsley and John M. Hayward, citizens of the United States, residing at Chatham, in the county of Morris and State of New Jersey, and at Crestwood, in the county of Westchester and State of New York, respectively, have invented a new, original, and ornamental Design for a Telephone Directory Cabinet, of which the following is a specification, reference being had to the accompanying drawings, forming a part thereof.

Fig. 1 is a front elevational view of the telephone directory cabinet showing our new design;

Fig. 2 is a side elevational view;

Fig. 3 is a top plan view; and

Fig. 4 is a longitudinal sectional view taken along line 4—4 of Fig. 1.

We claim:

The ornamental design for a telephone directory cabinet as shown.

HARRY I. BEARDSLEY.
JOHN M. HAYWARD.
